UNITED STATES PATENT OFFICE.

JEFFERSON D. MILLER, OF NEW YORK, N. Y.

STAIR-CARPET HOLDER.

SPECIFICATION forming part of Letters Patent No. 745,220, dated November 24, 1903.

Application filed April 4, 1903. Serial No. 151,186. (No model.)

To all whom it may concern:

Be it known that I, JEFFERSON D. MILLER, a citizen of the United States, residing at New York city, in the State of New York, have invented a new and useful Stair-Carpet Holder, of which the following is a specification.

This invention is an improved construction of stair-carpet holder or fastener, the object being to provide a cheap and simple device 10 by means of which the stair-carpet can be securely fastened at the angle formed by the juncture of the riser and tread.

Another object is to provide a stair-carpet fastener in which the parts shall be adjustable, so that the fastener can be made to accommodate different thicknesses of carpet; and a still further object is to provide a stair-carpet holder or fastener which can be used as well upon curved steps as straight ones; 20 and a still further object is to provide a carpet holder or fastener which can be quickly and easily attached to or detached from the steps and also one which can be applied or removed without the aid of skilled labor.

25 With these various objects in view my invention consists, essentially, in the employment of two angular metallic plates, one plate being connected to the riser of the step and the other plate to the tread of the step, each 30 plate being provided with a serrated or toothed edge, said serrated or toothed edges projecting toward each other and adapted to engage the carpet which is forced therebetween, the portions of the plate contacting with the riser 35 and tread being slotted, said slot being enlarged at one point sufficiently to receive the head of a screw, so that the plate can be attached to or detached from the step without removing the screws.

40 The invention consists also in arranging the slots obliquely, so that the plates can be adjusted toward or away from each other in order to accommodate various grades of carpet.

45 The invention consists also in making the strips narrower and providing them with ears, each ear being slotted in exactly the same manner as the plate, this construction of fastener being particularly adapted for use in 50 connection with curved steps.

The invention consists also in certain details of construction hereinafter fully described, and pointed out in the claims.

In the drawings forming part of this specification, Figure 1 is a perspective view showing the practical application of my invention, the balustrades of the stairs being omitted in order to more clearly show the invention. Fig. 2 is a face view of one of the holder or fastener plates, the screws being shown in 55 section. Fig. 3 is an edge view showing the relative positions of the plates when connected to the riser and tread of the stairs. Fig. 4 is a detail face view of the fastening-plate particularly adapted for use in connection 60 with curved steps. Fig. 5 is a top plan view showing the manner of applying said plate.

In carrying out my invention I employ a thin metal plate A, which is bent longitudinally along the line A', thereby providing 70 two portions A² and A³, the portion A² being secured to the riser or tread of the step, so that the portion A³ will extend obliquely away from the said riser or tread, as most clearly shown in Figs. 1 and 3, and the outer 75 edges of the portions A³ are toothed or serrated, as shown at A⁴, so that the stair-carpet, which is forced down between the toothed edges of the plates, will be securely held by the said teeth engaging the fold of the carpet forced between the said toothed plates, and no other fastening means will be necessary to secure the carpet at this point. The portions A² of the plates A are secured 80 to the riser and tread of the steps by means of screws B, said screws passing through the slots C produced in the said portions A², and it will be noted that these slots are arranged obliquely or at an angle with the edges of the plate, and the bottom edge of the slot has a 85 notch C' produced therein of such a size that the head of the screw will pass freely therethrough, and the top of the slot has a series of notches C² of a size convenient to receive the shank of the screw, as most clearly shown in Fig. 2, and before the screws are tightened 90 in the plates will be so arranged that the shanks of the screws will occupy the proper notches in the slots.

In Fig. 2 I have shown the screws as occu- 100

pying the central notches, and in case it should be desired to adjust the plates to accommodate a heavier grade of carpet the screws will be loosened and the plate moved 5 to one side, so as to bring the shanks of the screws into the bottom notches C², whereas if a thinner grade of carpet is to be accommodated the plates will be moved so as to bring the shanks of the screws into the upper notches C².

In Figs. 4 and 5 I have shown the construction I employ when fastening the carpet to curved steps and in which the plate A⁵ is made somewhat narrower than the plate A 15 and is provided with integral ears A⁶, which are bent at the same angle with the plate A⁵ as the portions A² and A³. Each ear A⁶ has an oblique slot C, which is arranged and operates exactly the same as the slots in the 20 portion A². This form of fastener bends easier; but its operation is identical with the fastener shown in Figs. 1 and 2.

In operation the screws are set at the proper points in the riser and tread of the steps. 25 The plates are then arranged and the screws tightened. The carpet is then folded and inserted between the toothed edges of the plate, and is thus securely held. Should it be desired to use the fasteners for holding a lighter

or heavier grade of carpet, the plates can be 30 adjusted, as heretofore described.

By using expansion-spring bolts instead of wood-screws the plates can be connected to stone or iron steps.

Having thus fully described my invention, 35 what I claim as new, and desire to secure by Letters Patent, is—

1. A stair-carpet fastener comprising an angular plate, having a toothed edge, said plate having oblique slots, substantially as de- 40 scribed.

2. A stair-carpet fastener comprising an angular plate, having a toothed edge, said plate having oblique slots, said slots having an enlargement upon the lower side and a plural- 45 ity of notches in the uppersides, substantially as described.

3. A stair-carpet fastener comprising an angular plate having a toothed edge, said plate having ears, said ears having oblique slots, 50 said slots being enlarged upon the lower side and notched at the upper side, substantially as described.

JEFFERSON D. MILLER.
